UNITED STATES PATENT OFFICE.

ANDREW J. HOYT, OF PHILADELPHIA, PENNSYLVANIA, ASSIGNOR OF ONE-HALF TO FRANKLIN HOYT, OF SAME PLACE.

ELECTRIC PUSH-BUTTON.

SPECIFICATION forming part of Letters Patent No. 394,925, dated December 18, 1888.

Application filed May 17, 1888. Serial No. 274,144. (No model.)

To all whom it may concern:

Be it known that I, ANDREW J. HOYT, a citizen of the United States, and a resident of Philadelphia, Pennsylvania, have invented 5 certain Improvements in Electric Push-Buttons, of which the following is a specification.

The object of my invention is to so construct an electric push-button that the signal will be given only when the button is being 10 depressed, the signal ceasing when the button has reached the limit of its inward movement and failing to sound on the backward movement of the button. This object I attain in the manner hereinafter set forth, reference being had to the accompanying drawings, in which—

Figures 1, 2, 3, and 4 are sectional views of 15 an electric push-button embodying my invention, the movable parts being in different positions in the different views. Fig. 5 is a perspective view of the device with the inclosing cap or cover removed, and Fig. 6 is a sectional view illustrating a modification of the invention.

20 In the push-button shown in Figs. 1 to 5, A represents the base, and x and y the opposite terminals of an electric circuit, these terminals being properly secured to the base and connected to the positive and negative wires 25 of the battery or other generator of electricity. The terminal x is in the form of a spring-finger having a rounded upper end, x', this finger projecting above the base and into the chamber within an inclosing cap or cover, B.

30 The terminal y forms part of a spring, y', which carries a block, D, of insulating material, and upon the latter bears the button F, which projects through an opening in the cap or cover B. Hung to one side of the block D 35 is a lever, a, the long arm of which when the block is in its elevated or normal position, as shown in Fig. 1, bears upon the terminal y, the short arm of the lever being free from contact with the terminal x. When the but-

40 ton F is pushed inward, however, the block D is depressed and the short arm of the lever a is brought into contact with the terminal x, so as to make connection between the two terminals, complete the circuit, and effect the 45 sounding of the alarm, the circuit being closed 50 during the time that the button is being de-

pressed. (See Fig. 2.) Just before the button reaches the limit of its inward movement, however, the short arm of the lever a passes the center of the rounded upper end of the 55 terminal x, and said lever is therefore, owing to the elasticity of said terminal, caused to swing upon its pivot, as shown in Fig. 3, so that the long arm of the lever is lifted from contact with the terminal y. The insulating-block D is now interposed between the two terminals; hence the circuit is broken and there will be no sounding of the signal during the time that the button F is held in the depressed position, nor will there be any 60 sounding of the signal while the button is moving outward to its normal position, for during this movement the short arm of the lever a is under control of the rounded end of the spring-terminal x, and the long arm of 65 said lever is thereby held in the elevated position shown in Fig. 4, a pin, b, on the block D serving to limit the upward movement of this portion of the finger. Just before the button F reaches the limit of its outward 70 movement, however, the short arm of the lever a passes from under the control of the rounded end of the terminal x and said lever swings on its pivot, the long arm of the lever dropping into contact with the terminal y, so 75 that the parts are again in position to complete the circuit on depressing the button.

The interposition of the insulating-block between the terminals on the completion of the movement of the button and the maintenance of this block between the terminals on the return movement are the main features 80 of my invention, and this may be effected in different ways. For instance, in Fig. 6 I have shown a modified form of push-button embodying my invention. In this case the stem a' of the push-button itself forms the connection between the terminals, this stem sliding in the terminal x and having a conical head, d, and a collar, f, between which is interposed 85 a sliding block, D', of insulating material. When the button F is first depressed, therefore, the conical head d comes in contact with the terminal y and completes the circuit; but as the movement of the button is continued 90 the collar f on the stem strikes the block D' and pushes the same forward over the termi- 95 100

nal y , so as to break the circuit, and on the return movement of the button the head d of the stem first enters a socket in the block D' and then causes the retraction of the latter, so that there is no contact between said head and the terminal y on the return movement. The main distinction between this device and that shown in Figs. 1 to 5, it will be noticed, is that whereas in the latter the contact-piece is hung to and movable on the insulating-block in the modified device the insulating-block is carried by and movable on the contact-piece, which in this case is the stem of the button.

Having thus described my invention, what I claim, and desire to secure by Letters Patent, is—

1. The combination, in an electric push-button, of the terminals, the contact-piece normally out of contact with one of the terminals, but brought into contact therewith on the depression of the button, and an insulating-block movable with said contact-piece and interposed in the electric path between the terminals on the depression of the button, all substantially as specified.

2. The combination, in an electric push-button, of the terminals, the contact-piece, and an insulating block movable with said contact-piece and interposed in the electric path between the terminals on the depression of the button, said contact-piece being also free to move independently of the insulating-block, all substantially as specified.

3. The combination of the terminals with the push-button and an insulating-block acted on thereby and carrying a pivoted contact-lever, all substantially as specified.

4. The combination of the terminals, the push-button, and the spring-supported insulating-block carrying the pivoted contact-lever, and having a stop-pin for restricting the swinging movement of said lever, all substantially as specified.

In testimony whereof I have signed my name to this specification in the presence of two subscribing witnesses.

ANDREW J. HOYT.
